CASING INSTALLING MACHINE

Robert K. Pepper, 216 E. Florence Ave., Syracuse, N.Y.

Filed Aug. 11, 1958, Ser. No. 754,341

7 Claims. (Cl. 255—20)

This invention relates generally to apparatus for driving tubes or casings through the ground, and has special reference to an improved machine for installing long metal casings under highways, railways and the like where open trenches are not permitted.

The applicant is aware of the fact that various types of earth boring or drilling machines have been developed heretofore for the above mentioned purpose, but most of these machines have not met with anything but limited acceptance because of undue complexity and cumbrousness and also because of the expense of manufacturing and operating them. Of the machines that have been used more extensively, practically all have one or more objectionable features, as for example, the inability to cope with large rocks or boulders that may be encountered, the use of water jets to flush out the loosened material, or the use of projecting drilling or cutting heads which tend to create pockets or voids in the surrounding material thereby causing settling of the overhead structure and which also prevent the entrance of large stones, etc. into the casing.

The present invention, therefore, contemplates and has as its broad objective the provision of a casing installing machine which has a comparatively simple construction and at the same time has none of the objectionable features noted above. This machine is specifically designed for the purpose of laying or installing a metal casing for use as a culvert or as a sewer, water or gas line under any structure or through any embankment where an open trench would be impractical or impossible.

Another important object of the invention is to provide a casing installing machine which is a self-contained complete unit that can be quickly put into operation at the job site.

Still another important object of the invention is to provide a casing installing machine which is simple to operate and wherein the rate of advance of the casing into the embankment can be carefully controlled by a positive, powerful manually controlled drive unit.

A further important object of the invention is to provide a machine of the character described which is capable of installing casings of long lengths and of varying diameters.

Another important object of the invention is to provide a machine of the character described which insures substantially straight penetration of the casing, provision being made for rear guiding of unusually long casings when necessary.

A still further important object of the invention is to provide a machine of the character described wherein provision is made for supplemental rotational driving power in installations involving penetration into very hard packed or dense material.

A more specific object of the invention is to provide a casing installing machine wherein the casing itself is rotationally driven and a cutting head capable of cutting through large stones is secured directly to the forward or embankment entering end of the casing.

Another specific object of the invention is to provide a casing installing machine wherein both the forward and rear ends of the casing are relatively unobstructed to enable the passage of large stones and rocks therethrough and also to allow the full length of the rotating casing to be observed by means of a flood light for the guidance of large rocks, portions of stumps, etc.

Still another specific object of the invention is to provide a casing installing machine having a free floating worm of substantially smaller diameter than that of the casing for removing the embankment material that has been cut or loosened by the cutting head. This worm assembly can easily be withdrawn from the casing to allow a man to crawl into it and drill or blast boulders or the like that are too large to pass through the casing.

Other objects and advantages of the invention will become apparent from the following detailed description thereof read in conjunction with the accompanying drawings which illustrate a representative embodiment of the invention for the purpose of disclosure.

In the drawings:

Figure 1 is a side perspective view of a casing installing machine embodying the invention with parts being broken away to show details thereof;

Figure 2 is a side perspective view corresponding to Figure 1 showing a slightly modified arrangement of the machine;

Figure 3 is an end elevation of the reciprocably movable frame of the machine;

Figure 4 is an end elevation corresponding to Figure 3, with some parts omitted, showing the manner in which the machine may be adapted for the installation of casings of varying diameters;

Figure 5 is a side elevation of the reciprocably movable frame;

Figure 6 is a detailed side elevation, partly in section, showing the track engaging rollers and propelling means for the frame;

Figure 7 is a substantially horizontal section through the structure shown in Figure 6;

Figure 8 is a detailed perspective view showing the manner in which sections of the worm are connected together; and

Figure 9 is a detailed perspective view of a cutting head having removable teeth.

Having reference now to the drawings, wherein like reference numbers designate the same part in each of the views, 10 indicates a cylindrical metal casing that is to be installed in or passed through an embankment indicated at 11 in Figure 1. In the drawings, the casing is positioned for substantially horizontal penetration into the embankment, but the machine to be described is not limited to horizontal operation since it can also be utilized in making upgrade or downgrade installations. In accordance with the invention, a cutting head 12 is telescopically positioned on the forward or embankment entering end of the casing and is releasably secured thereto as by bolts or the like. The cutting head may be formed with integral ground teeth as shown in Figures 1 and 2, or it may be provided at its leading edge with a plurality of replaceable hardened steel teeth 14 as shown in Figure 9.

In the embodiment of the invention illustrated in Figure 1, the casing 10 is supported by single cylindrical sleeve or barrel 15 which encircles the casing and is provided with a plurality of relatively large set screws 17 that can be turned inwardly to secure the casing to the sleeve. The sleeve itself is rotatably mounted in a frame 18 where it is supported adjacent each end by a plurality of idler rollers 20, Figure 3, the idler rollers being carried by cross plates 21 secured to the ends of the frame.

Sleeve 15 and the casing secured thereto are adapted

to be rotationally driven by means of a power unit 22, preferably a gasoline engine, which is detachably secured to the top of frame 18. To this end, the sleeve is provided with an external ring sprocket 24 located midway between its ends, and this sprocket is connected by means of a chain 25 to a gear reduction unit 27 which is connected by a second chain 28 to the engine output shaft.

The support frame 18 is mounted for reciprocable movement on a track comprising a pair of I-beams 30 secured together in spaced, parallel relation by end members 31, and is guided during such movement by a plurality of depending guide brackets 32 which extend under the outer flanges of the beams as shown in Figures 3 and 4. The track may rest on suitable ties 33 and is positioned so that it extends towards the embankment in the direction in which it is intended to have the casing penetrate. Each side of the frame 18 is equipped with a pair of track engaging rollers 34, the shafts for the rollers on each side being journaled in a pair of parallel plates 35 extending between the corner angle bars 37 of the frame at the bottom thereof, see Figure 7.

Frame 18 can be propelled in either direction along the track by means of a hand wheel 38 which is located on the upper rear side of the frame as shown in Figure 5. This wheel is mounted on the end of a horizontal shaft 40 that operates through a gear box 41 to turn a vertical shaft 42, and the latter operates through a second gear box 44 to turn a horizontal shaft 45 which extends transversely across the bottom of the frame. Shaft 45 is also journaled in the parallel plates 35 on each side of the frame, and a spur wheel 47 is keyed thereto between each pair of plates. The teeth or lugs on the spur wheels mesh with rows of holes 48 formed in the end flanges of the track I-beams whereby rotation of the spur wheels by means of the hand wheel 38 operates to drive the frame along the track.

To prevent dirt, gravel or other adventitious matter from interfering with the frame rollers 34 and spur wheels 47, a removable cover plate (not shown) is positioned over each of the pairs of parallel side plates 35 when the machine is in operation to form a protective enclosure for these parts. Mounted in parallel relation to the hand wheel shaft 40 on top of the frame 18 is an alternate hand wheel shaft 50, Figure 3, carrying a small sprocket 51 which is connected by a chain 52 to a larger sprocket 53 on the shaft 40. By transferring the hand wheel 38 to the alternate shaft 50 this drive becomes a speed reduction device, and it simply idles when the hand wheel is mounted on shaft 49 for a direct drive as shown in the drawings.

From the description thus far it will be seen that when the casing 10 is rotated by the power unit 22, and the frame 18 is moved towards the embankment by its manually operated drive, the cutting head 12 will cut into the embankment with much the same action as a milling cutter. The manual control of the rate of advance is advantageous in this connection because it enables a trained operator to adjust and vary the rate in accordance with the type of material encountered. Thus, the material of the embankment might be hard packed or loose, wet or dry, dirt or gravel, etc., and the operator learns to judge these varying conditions by "feel" and adjust the rate of advance accordingly.

In order to remove the embankment material that is cut loose by the cutting head, the machine is provided with a rotatable worm 55 which is positioned in the bottom of the casing 10 as shown in Figure 1, the worm having an over-all diameter that is substantially less than the inner diameter of the casing. This worm does no cutting or drilling and cannot do so because its forward end 57 terminates at a point spaced inwardly or rearwardly of the forward end of the casing. The rear end of the worm projects outwardly beyond the rear end of the casing where it is connected by a universal coupling 58 to an independent power unit unit 60 that drives the worm.

The power unit, which is preferably a gasoline engine, is supported in suspended relation rearwardly of the casing by means of a pipe or rod 61 one end of which is received in the sleeve 62 of a bracket and sleeve arrangement on the engine and the other end of which is received in the sleeve 64 of a saddle unit 65. The saddle unit rides on the rear end of the casing by means of rollers 67 and is held in position thereon by a second pipe 68 which extends from the sleeve 64 to a sleeve 70 on the support frame 18.

The spacing of the forward end of the worm inwardly from the forward end of the casing is important since the worm should be able to keep the casing relatively clear of loose material but should not allow the material to pour freely into the forward end of the casing where excessive weight could cause downward bending. This optimum condition is approximated when the loose material entering the casing has about a 1 to 1 or 45° slope, as indicated at 71 in Figure 1, and the end of the worm terminates just inside the lower portion of the slope. When such is the case, the loose material at the end of the casing acts as a natural bulkhead which prevents the free flow of material into the casing as would happen if the worm extended to the end of the casing or beyond and the embankment material were at all loose. Allowing an excessive amount of loose material to pour into the casing is, of course, undesirable since this tends to create voids or pockets in the surrounding embankment which could cause a road on the top of the embankment to settle. With the worm terminating as above described, however, the natural bulkhead is formed and the worm carries away the loose material at a rate which allows this bulkhead to be maintained with the desired slope as the casing is advanced.

The diameter of the worm in relation to the inner diameter of the casing is also very important in the operation of the machine. Thus, unlike other machines wherein the worm fills the interior of the casing or driven member, the worm in the illustrated embodiment of the invention has a diameter which is a little less than half the inner diameter of the casing. This allows relatively large rocks or boulders to be conveyed out of the casing as is indicated at 72 in Figure 1, and it has been found that a worm of this size is more than adequate for removing the finer loose material at the desired rate. In addition, the small diameter of the worm and the flexible drive coupling at its rear end allow the worm to be both laterally and upwardly displaced within the casing so that it is in effect free floating therein. With this arrangement, the possibility of a rock becoming wedged between the worm and casing is very remote.

The machine is prepared for operation by placing a section of casing in the sleeve 15 and sliding it forward until its forward end abuts against the embankment. The frame 18 and sleeve are then moved rearwardly relative to the sleeve to a position towards the rear end thereof at which time the set screws 17 are tightened to connect the sleeve and casing together. A section of worm of the right length and diameter for the casing is then positioned therein and the worm drive 60 is connected to the rear end of the worm and to the frame. In a relatively short section of casing, when the frame is initially positioned close to its rear end, the saddle unit 65 may be omitted as shown at the left side of the arrangement disclosed in Figure 2. However, if the casing section is long, the frame and sleeve may initially be connected near the middle of the section in which case a saddle unit would be employed for added support as indicated in Figure 1.

Having connected the casing and frame as above described, the rotational drive unit 22 is started and the frame is moved forward on the track by its manually operated drive means thereby causing the casing to cut into the embankment. At the same time, the worm

drive is actuated to effect the removal of the loose material cut from the embankment as above described. When the frame reaches the forward end of the track all of the drive means are stopped and the worm drive is disconnected from the frame and the worm itself, and the set screws 17 connecting the sleeve and casing are loosened.

The frame is then moved rearwardly on the track to a position close to the rear end of the casing, if it had previously been connected near its mid-point, or, a new section can be added on as by welding and the frame can be moved rearwardly to a point on the new section. In either case, the set screws are again tightened down on the casing, and the worm drive is re-connected using whatever length of pipe 61, or lengths of pipes 61 and 68 with a saddle unit, that may be necessary to properly locate the drive relative to the rear end of the worm. Thereafter, the various drives are again put into operation to advance the casing further into the embankment. Whenever a new section of casing is added, a new section of the worm will also be added, the sections being joined as by a common plug 74, Figure 8, which may be telescopically received in and bolted to each section.

The above described procedure is continued until the casing has been driven all of the way through the embankment, at which time the cutting head is removed from the forward end and the rest of the machine removed from the rear end.

Since the casings to be installed will vary in diameter from job to job, the installing machine is equipped with sleeves of various sizes to accommodate the different standard sizes of casing. In order to properly guide the different sleeves during rotation, the upper roller supporting cross plates 21 can be raised or lowered as indicated in Figure 4, there being a series of bolt holes 75 in each corner bar 37 of the frame to enable proper positioning of the guide rollers for each sleeve size.

Figure 2 illustrates a slightly modified arrangement of the machine which is sometimes employed for installing unusually long sections of casing. In this arrangement, two of the reciprocably movable frames are utilized, with the rear frame 18' serving as an alignment guide and as a support for the worm drive 60. Normally, only the forward frame 18 will be equipped with a power unit 22 to rotate the casing, and the rear sleeve 15', which is also connected to the casing by its set screws, will simply turn with the casing and keep the rear end thereof in alignment. However, if very hard packed embankment material is encountered and rotation of the long casing becomes difficult, a second power unit (not shown) can be easily lowered onto the rear frame and put into operation to provide more power for the rotational drive.

From the foregoing description it will be apparent that the invention described herein provides a novel and highly practical casing installing machine which eliminates most of the disadvantages of the prior machines of the same type. As will be apparent to those familiar with the art, the invention may be embodied in other specific forms without departing from the spirit or essential characteristics thereof. The embodiments disclosed are therefore to be considered in all respects as illustrative and not restrictive, the scope of the invention being indicated by the appended claims.

What is claimed is:

1. In a machine for the underground installation of a cylindrical casing, an unobstructed cylindrical cutting head adapted to be removably attached to the forward, ground entering end of said casing, support means for the casing releasably secured thereto rearwardly of its forward end, a first power operated means to rotate said support means and the casing secured thereto, manually operated means to move said support means to advance the casing into the embankment, a free floating worm adapted to lie on the bottom of the casing, the over-all

diameter of said worm being substantially less than the inner diameter of the casing, the forward end of said worm terminating rearwardly of the forward end of the casing, a second power operated means connected to said casing support means and adapted to drive said worm, and a flexible coupling connecting said drive means with the rear end of said worm to permit lateral or upward displacement of the worm within the casing while it is being driven.

10 2. A machine as defined in claim 1 wherein said support means comprises a cylindrical sleeve rotatably mounted in a reciprocably movable support frame.

15 3. A machine as defined in claim 1 wherein said support means comprises a pair of cylindrical sleeves secured to the casing in spaced relation to one another, each of said sleeves being rotatably mounted in a reciprocably movable support frame.

20 4. A machine as defined in claim 3 wherein one of said cylindrical sleeves is adapted to support the rear end of the casing.

25 5. In a machine for installing a cylindrical casing in an embankment, the combination of a cylindrical unobstructed cutting head adapted to be releasably attached to the forward, embankment entering end of the casing, a track extending towards the embankment in the direction that the casing is intended to pass therethrough, at least one support for the casing including a frame mounted for reciprocable movement on said track and a cylindrical sleeve rotatably mounted in said frame, 30 said sleeve being adapted to be releasably secured to the casing rearwardly of the forward end thereof, power operated means mounted on said frame to rotate said sleeve and the casing therewith, means to move said frame towards said embankment to cause penetration of the forward end of the casing therein, a free floating worm adapted to be positioned in the bottom of the casing with its forward end terminating at a point spaced inwardly from the forward end of the casing, the overall diameter of said worm being substantially less than the inner diameter of the casing, independent power operated means connected to said movable frame and adapted to drive said worm, and a flexible coupling connecting said drive means with the rear end of the worm to permit lateral and upward displacement of the worm 45 while it is being driven within the casing.

6. In a machine for installing an elongated cylindrical casing in an embankment, the combination of a cylindrical cutting head adapted to be releasably attached to the forward, embankment entering end of the casing, said cutting head having a plurality of replaceable cutting teeth about the periphery of the leading edge thereof, a track extending towards the embankment in substantially the direction that the casing is intended to pass therethrough, supporting means for the casing including a pair 50 of frames mounted for reciprocable movement on said track and a cylindrical sleeve rotatably mounted in each of said frames, said sleeves being adapted to encircle the casing and having means to releasably secure the casing thereto, one of said sleeves being adapted to engage the 55 casing rearwardly of the forward end thereof and the other sleeve being adapted to engage the casing adjacent the rear end thereof, power operated means mounted on at least one of said frames to rotate its sleeve and the casing therewith, manually operated means to move said 60 frames on said track towards the embankment, a free floating worm adapted to be positioned in the bottom of the casing with its forward end terminating at a point spaced inwardly from the forward end of the casing and its rear end projecting outwardly beyond the rear end of the casing, the over-all diameter of said worm being less than one-half the inner diameter of the casing, independent power operated means supported by said rearwardly located support frame and adapted to drive said worm, and a universal coupling connecting said drive means with the outwardly projecting rear end of said 70 75

worm to permit lateral and upward displacement of the worm while it is being driven within the casing.

7. In a machine for installing a cylindrical casing in an embankment, an unobstructed cylindrical cutting head adapted to be removably attached to the peripheral edge of the forward, embankment entering end of the casing whereby said forward end is completely unobstructed, a track extending towards the embankment in the direction that the casing is intended to pass therethrough, a support for the casing including a frame mounted for reciprocable movement on said track and a cylindrical sleeve rotatably mounted in said frame, said sleeve being adapted to encircle said casing intermediate the ends thereof and having means to releasably secure the casing thereto, power operated means mounted on said frame to rotate said sleeve and the casing therewith, means to advance said support on said track towards the embankment, a free floating worm positioned adjacent to the bottom of the casing, the over-all diameter of said worm

being substantially less than the inner diameter of the casing, the forward end of said worm terminating rearwardly of the forward end of the casing, and independent power operated means to drive said worm.
